UNITED STATES PATENT OFFICE.

ERNEST L. CONDON, OF MEDWAY, MASSACHUSETTS, ASSIGNOR TO UNITED SODA FOUNTAIN COMPANY, OF BOSTON, MASSACHUSETTS, A CORPORATION OF MASSACHUSETTS.

ICE-CHEST CONSTRUCTION.

1,413,576.

Specification of Letters Patent. Patented Apr. 25, 1922.

Application filed January 6, 1920. Serial No. 349,803.

To all whom it may concern:

Be it known that I, ERNEST L. CONDON, a citizen of the United States, and resident of Medway, in the county of Norfolk and State of Massachusetts, have invented new and useful Improvements in Ice-Chest Constructions, of which the following is a specification.

This invention relates to ice box construction and particularly to the construction of ice boxes or chests forming part of a soda fountain installation.

According to the most modern and approved practice in soda fountain construction, the soda fountain installation comprises a serving counter or shelf at the rear (considered from the point of view of the dispenser), a row of syrup pumps, soda faucets etc., in front of the counter, and in front of the syrup pumps, faucets, etc., an ice box or chest which stands about the height of an ordinary table and extends along the front of the installation. This ice chest is usually provided with openings in its top protected by suitable covers, for inserting and removing cans of ice cream, and for serving the ice cream, also compartments for various articles to be chilled, and also chambers and compartments for holding broken ice. For the best results the walls of the ice chest must contain heat insulation, must be tightly sealed to prevent moisture from penetrating to the interior of the insulating walls and injuring the insulation and other material, and must be made strong and resistant to the rough usage to which such chests are subjected as hereinafter more fully indicated.

The principal object of the present invention is to improve the construction of such ice boxes to attain these ends.

The accompanying drawing, which illustrates a preferred embodiment of the invention, shows a vertical cross-section of the upper front longitudinal corner of an ice box showing the details of the invention.

The front or outer facing *a* of the ice chest wall usually extends upward from the floor to the top of the chest, and preferably consists of a slab of marble or similar material.

The inner face of the wall is lined with sheet metal *b*, preferably sheet copper or other metal adapted to resist rust and corrosion; and between the outer facing *a* and the

inner lining *b* is a packing *c* of cork or other heat insulating material.

At the top of the wall is a slab of slate or similar material *d*, set inside of the facing *a* and covering the whole space occupied by the insulation. The slab *d* is secured in position by means of brackets *e*, of which there may be as many as necessary, depending on the size of the structure, fastening to the slabs *a* and *d* by screws *f* and *g*.

The top of the wall structure is covered and bound with sheet metal, preferably nickel silver *h* bent down over the edge of the facing *a* as shown at *i*, and secured by screws *j* extending into plugs *k* of wood, lead, or other suitable material, set into bores in the slab *a*. The rear edge of the cover sheet is also bent down to form the depending flange *m*.

The joint between the flange *m* and the lining *b* must satisfy a number of exacting conditions. It must be moisture proof to prevent water from melting ice and other sources from getting into the interior of the wall and injuring the insulation. It must be capable of being soldered while the box is in normal position because the box is very heavy and cumbersome and cannot be readily tipped on its side or upside down like a small article; an ordinary straight lap joint is not practicable because there is nothing to hold the solder until it hardens. It must be very strong to resist strains on the lining due to the weight of ice and the practice of dispensers to chop and pound the ice within the box. To these ends the upper margin of the lining is bent downwardly upon itself as shown at *n*, and thence upwardly as shown at *o*, the parts *n* and *o* forming a channel, open at the top, into which the edge of flange *m* fits. The part *n* is soldered to the body of the lining *b* before the lining is put in place, and the flange *m* is soldered within the channel between *n* and *o* while the box is standing in normal position.

The upwardly facing channel member enables the latter soldering operation to be successfully performed since the channel holds the solder while it is still soft. Thus a tight, strong joint is provided, and one which can be sealed while the chest is standing in normal position.

The upper edge of facing *a* is beveled or inclined rearwardly as shown at *p*, and the cover sheet *h* is correspondingly bent, to pre-

vent water or other moisture which may accumulate on top of the box, from dripping down the front of the facing.

It is desirable that the top slab *d* be made of slate or other stone, rather than wood or iron, because in use it has to withstand heavy shocks and blows from containers, etc., which are commonly rested on the box incidentally to filling the box, and which would dent the cover sheet *d* if it were supported by a backing of wood; and because if iron were used it would tend to rust and deteriorate. A part of the top wall of the chest is indicated at *g*.

16. I claim:

1. Wall construction for an ice chest comprising a front facing, a sheet metal lining terminating in a horizontal edge below the plane of the top of the front facing, a packing of heat insulating material between the front facing and the lining, a slab at the top of the wall over the space occupied by the insulating material, and a cover of sheet metal the front margin of which is bent down over the front facing and the rear margin of which is bent down and sealed to the upper edge of the lining.

2. Wall construction for an ice chest comprising a front facing, a sheet metal lining terminating in a substantially horizontal edge below the plane of the top of the front facing, a packing of heat insulating material between the front facing and the lining, a slab of stone at the top of the wall over the space occupied by the insulating material, brackets fastened to the front facing and to the slab for supporting the latter in position, and a cover of sheet metal the front margin of which is bent down over the front facing and the rear margin of which is bent down and sealed to the upper edge of the lining.

3. Wall construction for an ice chest comprising a front facing, a sheet metal lining provided with an upwardly facing channel, a packing of heat insulating material between the front facing and the lining, a slab at the top of the wall over the space occupied by the insulating material, the upper surface of said slab being substantially horizontal, and a cover of sheet metal resting upon the upper surface of said slab, the front margin of said cover being bent down over the front facing and the rear margin thereof being bent down and soldered in the upwardly facing channel on the lining.

4. Wall construction for an ice chest comprising a front facing, a sheet metal lining the upper margin of which is bent downwardly upon itself and thence upwardly to form an upwardly facing channel, a packing of heat insulating material between the front facing and the lining, a stone slab at the top of the wall over the space occupied by the insulating material, and a sheet metal cover overlying said slab, the front margin of said cover being bent down over the front facing and the rear margin thereof being bent down and extending into and being soldered to the channel on the lining.

5. An ice chest comprising a side wall having a metallic lining member provided adjacent its upper edge with an upwardly opening channel, a metallic casing for the outer surface of said wall, said casing being provided with a downwardly directed flange having its lower edge seated in said channel, and a fusible material within said channel and connecting said flange and lining member.

Signed by me at Boston, Massachusetts, on this 30 day of December 1919.

ERNEST L. CONDON.
